Walter E. Moore, St. Louis County, Mo., assignor
to Swing-A-Way Manufacturing Company, St.
Louis, Mo., a corporation of Missouri

Application August 9, 1950, Serial No. 11,694

Term of patent 14 years

(Cl. D22—2)

To all whom it may concern:

Be it known that Walter E. Moore, a citizen of the United States, residing in St. Louis County, State of Missouri, has invented a new, original, and ornamental Design for a Can Opener, of which the following is a specification, reference being had to the accompanying drawing, forming a part thereof, in which:

Fig. 1 is a plan view of a can opener embodying my new design;

Fig. 2 is a front elevational view thereof;

Fig. 3 is an end elevational view thereof, looking towards the left end as shown in Fig. 2; and

Fig. 4 is an end elevational view thereof, looking towards the right end as shown in Fig. 2.

The rear side of the can opener is flat.

I claim:

The ornamental design for a can opener, substantially as shown and described.

WALTER E. MOORE.
